UNITED STATES PATENT OFFICE.

DONALD D. JAMES, OF NEWTON, MASSACHUSETTS.

FOOT-REST FOR RADIATORS.

1,109,991.

Specification of Letters Patent. Patented Sept. 8, 1914.

Application filed August 9, 1912. Serial No. 714,266.

To all whom it may concern:

Be it known that I, DONALD D. JAMES, a citizen of the United States, residing at Newton, in the county of Middlesex, State 5 of Massachusetts, have invented certain new and useful Improvements in Foot-Rests for Radiators; and I do hereby declare the following to be a full, clear, and exact description of the invention, such as will enable 10 others skilled in the art to which it appertains to make and use the same.

This invention relates to improvements in attachments for steam or hot water radiators and particularly to a foot rest attachment 15 therefor.

The principal object of the invention is to provide a simple device of this character which may be quickly and easily applied to the coil of the radiator and in which the 20 foot rest bar may be readily adjusted to various angles.

Other objects and advantages will be apparent from the following description and with particular reference to the accompanying 25 drawings.

In the drawings: Figure 1 is a front elevation of a radiator showing my invention applied, Fig. 2 is an end view, Fig. 3 is a top plan view, Fig. 4 is a horizontal sectional view on the line 4-4 of Fig. 2, slightly enlarged, Fig. 5 is a horizontal sectional view 20 on the line 5-5 of Fig. 2, Fig. 6 is a front elevation of one of the clamps detached.

Referring particularly to the drawings, I 35 provide a plurality of clamps 10 each of which comprises a pair of bowed jaws 11 for embracing engagement with the coils of a radiator. These jaws are connected to a head 12, which is provided with a central 40 perforation 13, and has concentrically arranged with this opening a series of outwardly extending teeth 14, which teeth are adapted for coöperation with similar teeth 15 on a head 16 of a supporting arm 16', 45 there being one of these arms 16' for each of the clamps, and all of the arms being attached to a foot plate 17. For holding the heads 12 and 16 together, I pass a bolt 19

through said head, and apply thereto a winged nut 20. By means of this, the arms 50 16' may be moved upwardly and downwardly on the bolt to adjust the foot plate 17 to various heights and angles.

On the outer face of each of the spring jaws at a suitable distance from the head 55 21, formed therethrough and transversely of the jaws are openings 22 through which is placed a clamping bolt 23 and a winged nut 24 on its threaded end, said bolt and nut 60 being adapted to press the jaws together and clamp them tightly to the coil of the radiator. On the inner face of each of the jaws is a vertically extending steadyng member 25, which members extend a short distance 65 above and below the said jaw, and are adapted for engagement against the front edge of the coils of the radiator to prevent the clamp rocking vertically on the coil of the radiator.

What is claimed is:—

A foot rest attachment for steam or hot water radiators including a clamp comprising a pair of bowed spring jaws for embracing engagement with the coil of the radiator, a foot plate adjustably mounted on the clamp, integrally formed bearing bosses on the spring jaws, a bolt passed through the bosses and the jaws for clamping the jaws to the radiator, and vertical fingers formed 75 on the inner faces of the clamping jaws and extending above and below the jaws, said steadyng fingers having their inner longitudinal faces transversely concaved and engaging with the front portion of the coil 80 of the radiator and on each side of the forward rib thereof so that the jaws are prevented from vertical rocking movement 85 thereon.

In testimony whereof, I affix my signature, in presence of two witnesses.

DONALD D. JAMES.
